REUBEN CALOW, OF CHICAGO, ILLINOIS.

INTERNAL-COMBUSTION ENGINE.

1,364,543.

Specification of Letters Patent.

Patented Jan. 4, 1921.

Application filed June 21, 1918. Serial No. 241,159.

To all whom it may concern:

Be it known that I, REUBEN CALOW, a citizen of the United States, residing at Chicago, in the county of Cook and State of Illinois, have invented certain new and useful Improvements in Internal-Combustion Engines, of which the following is a specification.

The present invention relates generally to 10 internal combustion engines, and more particularly to a novel arrangement and construction of certain conduits, and parts associated therewith, which operate in conjunction with heated portions of the engine 15 to supply to the explosive mixture a desired quantity of heated air.

Among the objects of this invention are 20 certain improvements in the construction of internal combustion engines by which economy is obtained in the consumption of fuel; by which greater engine efficiency is attained without an increase in fuel consumption; and by which the temperature of certain parts adjacent to other heated 25 parts is kept within desired limits.

My invention aims additionally to accomplish the above ends by means which are 30 inexpensive, unitary in construction, and hence easily attached, and certain in operation as well. Other objects will also herein-after appear from a detailed description of 35 the invention as contained in the accompanying specification and claims, and as exhibited in the accompanying drawings representing two embodiments thereof, wherein:—

Figure 1 is a side elevation of an internal combustion engine showing in longitudinal section a single manifold containing intake 40 and exhaust passages, with which the improvements of this invention are combined;

Fig. 2 is a transverse section taken on line 2—2 of Fig. 1;

Fig. 3 is a detail in section of a valve arranged either for automatic or manual control for regulating the amount of heated air supplied to the intake passage of the manifold;

Fig. 4 is a side elevation of an internal 50 combustion engine equipped with manifold of modified construction;

Fig. 5 is a transverse section taken on line 5—5 of Fig. 4; and

Fig. 6 is a plan view of the manifold 55 shown in Fig. 4.

The device to be herein described is shown in connection with a multi-cylinder internal combustion engine designed for automobile use, and designated generally by the numeral 5. Upon the side of the engine 60 is a combination intake and exhaust manifold 6, formed of a single casting and arranged for connection with the engine parts in the usual manner. This manifold is of novel construction, its various passages 65 being so disposed as to present an efficient and compact structure, as I will now proceed to explain.

A carburetor 7 of any approved type connects with the intake end 8 of a main passage 9 which communicates with two distributing passages 10 and 11, each of which is arranged to deliver the explosive mixture through outlet ports 12 and 13 respectively, forming gas tight connections with 70 suitable intake ports provided in the engine. In the form shown, the manifold is designed for use with a four cylinder engine having distributing passages leading from each intake port to the explosion 75 chambers of two cylinders, so that the manifold requires but two delivery ports 12 and 13 for distributing the mixture to all four cylinders. Such details of construction, however, are relatively unimportant to this 80 invention, as obviously the number and disposition of the outlet ports formed in the manifold will be governed, to a considerable extent at least, by the design of the engine 85 with which it is to be used. 90

These inlet ports to the engine are in practice generally aligned with other exhaust ports, one for each cylinder, through which the spent gases find egress, and to connect with such points of outlet the present manifold is also provided with ports marked 14, 95 each of which communicates with a main exhaust passage 15 to which a pipe 16 is connected to lead away the spent gases to any convenient point of exit. The exhaust passage 15 is preferably located above, and the mixture distributing passages 12 and 13 below, the line of ports entering the engine cylinders, but it is my purpose to so separate 100 these passages that the heat within the one will not undesirably affect the temperature of the other. Accordingly, as will be observed in Fig. 1, between each of the openings 12, 13, and 14 in the manifold connecting 105 with inlet and exhaust ports in the en- 110

gine, there is provided an intervening space 17, which receives at all times the cooling effect of the outside air, and serves, besides, as an opening through which a bolt 18, or other attaching medium, may connect with the engine to secure the manifold in place. It will be noted, therefore, that while the present construction is extremely compact, it provides, nevertheless, for a substantial separation between the intake and exhaust passages of the manifold, such that any extended interchange of heat units is rendered difficult.

In addition to the features of novelty already described, there is yet another improvement incorporated therewith, which makes for the efficiency of the present manifold. This consists of a tube or pipe 19 positioned within the exhaust passage 15 and arranged for the conduction of air to the main inlet passage 9 of the manifold. As appears from Figs. 1 and 2, this pipe has its inlet end 20 projected through the closed end of the exhaust passage of the manifold, is extended therewithin for practically the length of the manifold, is then bent upon itself as at 21, and at about midway of the length of the manifold, as at 22, takes a turn of ninety degrees or thereabout to pass through the walls which form the proximate air space 17, so as to enter the main inlet passage of the manifold. The delivery end 23 of the pipe 19 terminates in the passage 9 preferably slightly below the point where the mixture commences to travel into the distributing passages 10 and 11, and is so arranged as to deliver the air into the passage 9 in a direction which is counter to the flow of the combustible gases passing therethrough to the engine cylinders. The action resulting from a delivery of air in this manner into the main passage 9 is such as to cause a more thorough and more effective diffusion and commingling of the air with the explosive mixture—a very desirable end in internal combustion engines.

The amount of air passing through the pipe 19, as well as its temperature at the point of delivery, may be controlled to a considerable extent by providing a suitable throttle device at its inlet end 20. Such a device, designated generally as 24, is shown in Fig. 1, the details of a preferred construction being illustrated in Fig. 3. I regard it as desirable that this throttle device should be designed either for automatic or manually controlled operation, or both, and with this end in view the construction now to be described possesses special advantages. Referring particularly to Fig. 3, I make use of a casing 25, generally tubular in form to provide an interior chamber 26, and having its lower end open and threaded to receive a bushing 27, whose upper end is shaped to provide a valve seat for a ball 28. The

valve inlet is at the lower end of the bushing, as at 29, and its outlet is through a laterally projecting nipple 30 (see Fig. 1), through which is formed a passage 31 communicating with the chamber within the valve casing. The parts thus described operate whenever suction forces are present to lift the ball and thereby take in air through the pipe 19. The upper end of the casing 25 is provided with a manually controlled valve 75 which is, of course, closed when the ball valve is in operation. This second valve consists of a plug 32 rotatably arranged within an appropriate seat in the casing, and provided with an opening 33 adapted to 80 open up a passage for air to enter through the upper end 34 of the casing and thence pass through the outlet passage 31 into the pipe 19. The plug 32 may be equipped with an operating arm or lever 35 arranged for 85 connection with a control rod (not shown) leading from any convenient point of operation. If the throttle device is to be operated entirely manually, then a cap 36 should be secured to the bushing 27, as shown in 90 Fig. 3, to close the lower inlet, but its use may be dispensed with when it is desired to have a part automatic and a part manual control.

Now by referring to Figs. 4, 5, and 6, a modified structure of manifold will be seen. As this in most respects is similar to the one already described, I shall explain its construction only briefly.

The walls of the manifold of Figs. 4, 5, and 6 are formed to provide a main intake passage 40 connecting with two distributing passages 41 and 42, which terminate in outlets 43 and 44 respectively, adapted to communicate with intake ports formed in the engine. In line with such ports are other ports in the engine, through which the exhaust gases travel to pass through inlets 45 communicating with the main exhaust passage 46 of the manifold, through which they 110 are conducted and led away by means of a suitable eduction pipe 47. As in the case of the manifold of Fig. 1, the exhaust passage 46 is separated from the intake distributing passages 41 and 42 by spaces 47 through 115 which attaching bolts 48 may pass. Thus far the manifold under consideration is practically the same as the one already described at length.

Upon the outer side of the manifold I have arranged means for the conduction of air somewhat different from the pipe 19 of Fig. 1. This means consists of a box or chamber preferably cast integral with the manifold and formed to provide a main passage 49 extending substantially the length of the manifold, and then reversed upon itself for about half the length of the manifold to provide a section 50, which then turns toward the main intake passage 40 with which 130

it communicates as at 51. The disposition of the walls by which the air conduction passage is formed can clearly be seen by reference to Figs. 4 and 5. As in the case of the 5 manifold of Fig. 1, I prefer to control the air entering the conduction pipe by using a throttle device 52 of the same general character as that shown in detail in Fig. 3. As the manner of operation and results attained 10 are similar in all substantial respects to that already described in connection with Figs. 1, 2, and 3, it is thought that further explanation is unnecessary.

Throughout this specification I have explained the principal points of advantage 15 arising from (1) the use of a combined intake and exhaust manifold constructed in accordance with this invention; (2) the use of an air conduction passage within the 20 manifold having the major portion of its length exposed to the heat of the spent gases and its outlet end terminating within the main inlet passage adjacent to the distributing passages; and (3) the use of a suitable 25 throttle device, preferably arranged either for automatic or positive control, or both, by which the supply of heated air delivered into the inlet passage may be regulated; so that any further elaboration is not deemed 30 necessary. Of course, these several features are capable of modification without departing essentially from the spirit of my invention, and in so far as any such modification may incorporate or make use of the novel 35 and improved means defined in the appended claims, I desire that they shall be included within the scope of this patent.

I claim:

1. The combination with an internal combustion engine having inlet and outlet ports 40 therein, of a combination intake and exhaust manifold whose walls are formed to provide a main inlet passage adapted to receive the explosive mixture, a plurality of distributing 45 passages communicating therewith and having openings communicating with the inlet ports of the engine, and an exhaust passage having openings communicating with the outlet ports of the engine, the several 50 openings in the manifold being in substan-

tial alinement and the exhaust passage being located to one side, and the distributing passages to the other side, of the line of openings, the walls of the manifold being formed to provide also spaces open to the outside 55 air located between the walls forming the exhaust and distributing passages whereby said passages are separated at intervals, substantially as described.

2. In combination, a combined manifold 60 adapted to be applied to an internal combustion engine having walls formed to provide inlet and exhaust passages and inlets and exhaust openings communicating respectively with said passages, and said walls 65 being likewise formed to provide spaces open to the exterior between the exhaust and inlet passages, the several openings in the manifold being in substantial alinement, and an air conduit extending circuitously with a 70 wall in contact with the interior of the exhaust passage, then directly traversing an air space between the exhaust and intake passages and opening into the intake passage. 75

3. The combination with an internal combustion engine having inlet and outlet ports therein, of a combination intake and exhaust manifold whose walls are formed to provide a main inlet passage adapted to receive the 80 explosive mixture, a plurality of distributing passages communicating therewith and having openings communicating with the inlet ports of the engine, an exhaust passage having openings communicating with the 85 outlet ports of the engine, the several openings in the manifold being in substantial alinement, the walls of the manifold being formed to provide also spaces open to the outside air which separate the walls of the 90 exhaust and distributing passages, and an air conduction pipe arranged within the manifold extending through the exhaust passage and directly into the inlet passage, substantially as described. 95

REUBEN CALOW.
